UNITED STATES PATENT OFFICE.

LEONARD COLERIDGE DAVIS, OF FRINTON-ON-SEA, ENGLAND.

FEEDING BOTTLE.

1,403,148.

Specification of Letters Patent. Patented Jan. 10, 1922.

Application filed June 3, 1921. Serial No. 474,749.

To all whom it may concern:

Be it known that I, LEONARD COLERIDGE DAVIS, a British subject, residing at Frinton-on-Sea, in the county of Essex, England, have

5 invented certain new and useful Improvements in Feeding Bottles, (for which I have filed an application in England June 2, 1920, Patent No. 152,594,) of which the following is a specification.

10 This invention relates to feeding bottles for infants and has for its object to produce a feeding bottle formed in separable parts of which one part may serve as a cup-like receptacle adapted to withstand heat for use 15 in preparing and heating the infant's food.

It further has for its object to provide a bottle of which one part is formed as a cup-like receptacle that is free from projecting parts and is adapted to be easily and thoroughly cleaned.

20 A further object is to provide improved means whereby the separable parts may be readily and efficiently maintained in operative relation with an air-tight joint to form 25 a complete feeding bottle.

These and further objects will be made clear in the following description aided by the accompanying drawing, in which:—

Fig. 1 is a side view partly in section of a 30 feeding bottle and clamping device constructed in accordance with this invention and

Fig. 2 is a back view showing more clearly the clamping device shown in Fig. 1.

35 Similar letters refer to similar parts throughout the two views.

In the drawing *a*, *b* respectively designate the separable parts of the bottle. The part *a* comprises a domed cap of rigid transparent material (preferably glass) and is provided with a forwardly-extending neck *c* adapted to be fitted with a teat (not shown). The neck is inclined at about 45 degrees to the main axis of the bottle, so that the teat 45 may be maintained at the correct angle for feeding a reclining infant when the bottle is inverted. On the upper wall of the neck *c* is formed a lump or thickening *e* so as to form a saddle between the bead of the neck *c* and the thickening *e* immediately above the main axis of the bottle.

The lower edge of the upper part *a* is adapted to fit loosely within the expanded mouth of the lower part *b* as shown, a flange 55 or bead *d* being provided adjoining the edge of the upper member to prevent over-inser-

tion and also to form an abutment for an india rubber ring *f* adapted to be engaged between the said bead and the expanded rim of the lower part *b*.

60 The lower part *b* comprises a cup-like vessel formed of fireproof china, earthenware, glass, aluminium or other metal which may be enameled or otherwise protected, and may be graduated to measure the feed. It is essential that this part be formed of a material that is not damaged by heat so that it can be placed with safety on a gas or like stove to heat the food contained therein. In form it is free from corners or projections 65 and has an unrestricted mouth and smooth finish. It is provided with two external lugs *g* on opposite sides which are pierced to admit the ends of the wire *h*.

The parts *a*, *b* are illustrated as being oval 75 in cross-section and the saddle between the neck *c*, and thickening *e* is adapted to be positioned in line with and above the lugs *g* when the parts are assembled. In both the parts *a*, *b* all angles are rounded off to facilitate cleansing.

70 The clamping device consists of a wire *h* bent as shown in Fig. 2 to form a yoke, the ends being inserted into the holes provided in the lugs *g* by drawing these ends apart 75 and allowing them to spring back into position. This wire *h* is threaded through a roller *k* which is shaped to fit the saddle on the part *a* and is pierced eccentrically at *m* as shown in Fig. 1, and which is provided 80 with an arm *l* by means of which it may be rotated. The wire *h* is constructed of resilient material (such as steel) and the roller *k* with its arm *l* may be constructed of any suitable metal or other material. The arm is 85 shown in raised position in Fig. 2 for the sake of clearness.

80 The operation of the device is as follows: Assuming the yoke *h* to be rotated clear of the mouth of the cup-like receptacle *b*, the upper member *a* is placed in position together with the ring *f*. As the roller *k* is eccentrically mounted on the wire yoke *h*, it is rotated so as to give maximum inward clearance whereupon the yoke can be moved 100 up into the position shown, as the roller in its position of maximum inward clearance effectively clears the lump *e*. The roller then occupies the position shown in dotted lines in Fig. 1. If now the roller is rotated into 105 the position shown in full lines by the arm *l*, owing to the eccentricity of its mounting,

it presses the part *a* downwardly upon the part *b* and the said parts form an airtight joint owing to the provision of the rubber ring *f* which is thereby compressed and expanded laterally. The arm *l* is rotated until it contacts with the lump *e* in which position the boring *m* of the roller has moved past its position of maximum separation from the lugs *g*, and the strain on the arms of the yoke, therefore, tends to maintain the parts in their locked position.

Owing to the provision of a transparent upper part, the contents of the assembled bottle can be readily inspected, and owing to the form and construction of the lower part the latter can be readily used for mixing and heating liquid food and readily cleaned after use by means of a cloth inserted in the unrestricted mouth.

10 20 I claim:—

1. A feeding-bottle formed in two parts adapted to be fitted together and means for retaining the said parts in operative position comprising pierced lugs on one part, a wire yoke having its ends hingedly mounted in said lugs, a roller eccentrically mounted on the wire yoke, said roller being adapted to be engaged with an element of the surface of the other part.

2. A feeding-bottle formed in two parts, the upper part having a delivery neck, a bead on the rim of said neck, a lump on said neck spaced from said bead so as to form a saddle therebetween, pierced lugs on the lower part, 30 a resilient wire yoke hingedly mounted in said lugs, a roller eccentrically mounted on

said wire yoke, the said parts being adapted to be fitted together with the interposition of a resilient packing, the yoke being of such a size that when the parts are so fitted the 40 roller in its position of maximum inward clearance can be swung over the lump and in its position of minimum inward clearance engages with the saddle to press the two parts resiliently together.

45 3. A feeding bottle, comprising a cup-shaped vessel having an outturned rim, a cap having a rim portion adapted to engage the rim of the vessel, a packing ring adapted to fit between the rims, a member pivotally mounted on the vessel adapted to extend over and beyond the cap, and an element eccentrically and pivotally mounted on the member adapted to engage the cap and force it toward the vessel to compress the packing between 50 55 the rims.

4. A feeding bottle, comprising a vessel formed of fire-resistant material and having a bottom and side walls with an outwardly flaring upper edge portion, the contour of 60 the vessel including the flaring upper edge portion being smooth and unbroken on the interior thereof, a cap adapted to fit over the open upper end of the vessel having a bead on the outer surface thereof adapted to 65 engage the flaring portion of the vessel, whereby the contour of the vessel and cap is even and free from sharp projections permitting a thorough cleansing thereof, and means for holding the cap on the vessel.

70 In testimony whereof I affix my signature.
LEONARD COLERIDGE DAVIS.
